(57) CLAIM

The ornamental design for a curtain rod support, as shown and described.

DESCRIPTION

FIG. 1 is a perspective view of the curtain rod wall unit for one end of a curtain rod showing the new design;

FIG. 2 is a top view;

FIG. 3 is a front view;

FIG. 4 is a back view;

FIG. 5 is a view from the right hand side of FIG. 1; and,
FIG. 6 is a view from the left hand side of FIG. 1.

The broken line showing of a fragmented rod is for illustrative purposes only and forms no part of the claimed design.
